UNITED STATES PATENT OFFICE

WILLIAM H. FORD, OF BUFFALO, NEW YORK, ASSIGNOR TO LIQUID VENEER CORPORATION, OF BUFFALO, NEW YORK, A CORPORATION OF NEW YORK

INSULATION FOR THIRD RAILS

Application filed March 10, 1931. Serial No. 521,505.

My invention relates to improvements in insulations for third rails, and it embodies in its construction a system for supporting third rails and insulating the various sections there-
5 of.

Third rails used as current conductors are commonly employed in conjunction with railway tracks, the third rail being more or less co-extensive with the tracks and comprising
10 members of different cross-sectional forma-
tions.

It has heretofore been the practice of supporting third rails by means of insulators applied to the various members of the third rail;
15 said members invariably having been housed in with boards of wood and arranged in vari-
ous ways to prevent persons, finding it neces-
sary to cross tracks, from coming in contact
with the rails which carry current of a high
20 voltage.

Supporting insulators, or what are usually termed rail insulators, used up to the present time are made of porcelain or other fragile material and are comparatively expensive.
25 Moreover, no provision is made for fitting them to, or interfitting them with, the wooden boards used as protectors for the third rail.

It is one of the objects of my invention to provide a system in which self-retaining insulating sections or members are employed and effectively cover the various members of
30 the third rail in a manner that only the contact surface of the rail is exposed; the various members of the system, including the sup-
porting insulators, being constructed so that they may be quickly and easily applied to the third rail, and the covering sections or mem-
bers without fastening means of any kind,
35 and without the use of tools.

40 Another object of my invention is to pro-
vide an insulation covering for third rails, constructed so that, regardless of the cross-
sectional formation of any of the third rail sections or members, adjacent ends of the in-
sulation covering sections or members are of
45 substantially the same cross-sectional forma-
tion and interfit one with the other.

Another object of my invention is to pro-
vide an insulation covering for third rails,
50 which is impervious to the elements of the

weather and so constructed that oil, grease, brine, or other foreign substances such as are used in the upkeep of road beds and the tracks thereof, or such as are transported over the rails, will not come in contact with the
55 third rail.

A further object is the provision of an insulation covering which is non-shrinkable, non-warping, and non-breakable, and which will not swell, regardless of the weather con-
60 ditions, or conditions of use; and further-
more, one which possesses great dielectric strength, so highly desirable in third rail cov-
erings; also which is far superior to and great-
ly outlasts wood coverings of the type now so
65 commonly in use.

A further object is the provision of a water-
proof insulation covering for third rails
which, aided by its construction, assures com-
plete and thorough waterproof insulation,
70 eliminates short circuits and arcing of the
current, protects the rails from deterioration,
and requires only a small fraction of the time
for applying it to the third rail of any known
75 covering now extant.

A further object of my invention is the pro-
vision of an insulation covering in which the
inherent resiliency of the same tends to effec-
tively grip and cause retention of the covering
on the rail and which is so constructed that it
80 cannot split and expose dangerous rails.

A still further object of my invention is to provide an insulation covering which can be easily and quickly removed in sections for
85 inspection of, and making repairs to, or re-
placing rail sections, and which can be as
quickly replaced without in any manner in-
juring the same or affecting its gripping qual-
ities.

The invention consists in the novel features
of construction, in the arrangement and com-
bination of parts, and in the material from
which the various insulation members or sec-
tions are constructed, all as will be described
hereinafter and more particularly pointed out
95 in the subjoined claims.

In the drawings:

Fig. 1 is a plan view of a length of straight-
line railway track, shown in conjunction with
a corresponding length of third rail equipped
100

with my improved supporting insulators and insulation covering sections; the third rail shown in this figure being standard or straight-line rail sections supported at intervals by means of insulation supports secured to ties of the tracks.

Fig. 2 is a plan view of two parallel tracks having cross-over connections in the form of switches, such as commonly used, but the details of which are omitted, and in connection therewith showing third rails having sections of different forms equipped with my improved insulation means, consisting of assembled and interfitting covering sections and supporting insulators.

Fig. 3 is a plan view of portions of two tracks arranged at right angles and showing the same in conjunction with third rails having my improved insulating covering and supporting insulators applied thereto.

Fig. 4 is a side elevation of a portion of a third rail, showing the manner of supporting the same by means of a bracket and a supporting insulator carried by the bracket, also showing adjacent portions of said rails equipped with my improved insulation covering.

Fig. 5 is a plan view of a curved portion of a railway track in conjunction with a curved portion of a third rail, showing my improved insulation covering and supporting insulators in connection with said third rail.

Fig. 6 is a somewhat enlarged view of a third rail, broken to indicate added length and showing two different forms of insulation supports and several forms of insulation covering sections or members employed in my improved insulation system.

Fig. 7 is a side elevation of the parts illustrated in Fig. 6.

Fig. 8 is a side elevation of a third rail, showing sections thereof bonded together and also showing in longitudinal section certain insulation covering sections or members and my improved insulation support in connection with said third rail.

Fig. 9 is an enlarged cross-section through a supporting bracket for a straight-line rail section, taken on line 9—9, Fig. 7.

Fig. 10 is an enlarged cross-section through a supporting bracket for an offset rail section, taken on line 10—10, Fig. 7.

Fig. 11 is an enlarged cross-section through a straight-line rail section, taken on line 11—11, Fig. 7.

Fig. 12 is an enlarged cross section through a bonded rail section, taken on line 12—12, Fig. 7.

Fig. 13 is an enlarged cross section through a transition rail section, taken on line 13—13, Fig. 7.

Fig. 14 is an enlarged cross section, taken on line 14—14, Fig. 7, and illustrating the manner in which the contact shoe of a locomotive comes in contact with a transition or

an offset section and in which it travels in contact with said sections.

Fig. 15 is a perspective view of a transition rail section.

Fig. 16 is a longitudinal section through adjacent ends of adjoining sections or members of my insulation covering, showing the manner in which one is overlapped by the other.

Fig. 17 is a plan view of a portion of a third rail, showing an offset member of a third rail between straight-line or standard members.

Fig. 18 is an inverted perspective view of a straight-line section or member of my improved insulation covering.

Fig. 19 is an inverted perspective view of an offset section or member of the covering.

Fig. 20 is an enlarged cross section through a straight-line section or member of the covering.

Fig. 21 is an inverted perspective view of a bonding section or member used as part of my insulation covering.

Fig. 22 is an inverted perspective view of an offset bonding section or member used as part of my insulation covering.

Fig. 23 is a perspective view of a right hand transition section or member of the covering.

Fig. 24 is a perspective view of a left hand transition section or member of the covering.

Fig. 25 is an inverted perspective view of the transition section or member illustrated in Fig. 23, reversed end for end.

Figs. 26 and 27 are perspective views of the two parts forming each of the supporting insulators employed on a transition or an offset section of a third rail.

Figs. 28, 29 and 30 are perspective views of the three parts of a supporting insulator employed on a straight-line or standard section of a third rail.

Fig. 31 is a perspective view of the fastening medium employed to clamp the parts of the supporting insulators together and to fasten the so clamped parts to the supporting brackets of the third rail.

Referring to the drawings in detail, the numeral 32 designates the ties of a railway track, 33 the rails thereof. These rails are shown in cross-over relation in Fig. 3, while two parallel tracks are shown in Fig. 2, in which figure the two tracks are connected by cross-over or switch rails 34. At regular intervals, the ties are made somewhat longer and extend outwardly at one side of the track, as at 35, to carry third rail supporting brackets 36, which are bolted or otherwise fastened to the ties in a secure manner. Each bracket has an inwardly-directed upper end providing an inwardly-facing flat bearing surface

37 which may be slightly curved outwardly at its upper end, as at 38, and at its lower end it is provided with an inwardly-directed ledge or rib 39 serving as the main support

for a rail supporting-insulator adapted to receive within it portions of a third rail 41 formed of different cross sections at different regions along the rail.

5 The third rail illustrated is a bottom contact rail, and it comprises straight or straight-line rail sections 42, transition rail sections 43, and offset rail sections 44; these being commonly employed in bottom or under-contact 10 third rails.

10 Each straight-line rail section is of substantially I-formation having a head 47, a shoe contact portion 48, usually similar to the head 47 in cross-sectional formation, and 15 a connecting web 49.

15 Each of the transition rail sections has offset parallel end portions 50, 51, and an oblique intermediate portion 52 connecting said offset end portions. One of the offset end portions 20 is similar in cross-sectional formation to the straight-line rail sections, against one of which it abuts, and the other end has its head 53 similar to the head of a straight-line rail section while the shoe contact portion 54 is 25 transversely widened laterally in opposite directions and has its under side serving as a contact surface inclined upwardly and inwardly toward the railway track, as at 55. The transverse widening of the shoe contact 30 portion is considerably greater at the inner side of the rail than the outer side thereof, and this transversely widened or extended contact surface 55 is gradually reduced so as to merge into the regularly-formed contact 35 surface at the opposite offset end portion of the offset section; and with this in view the inner edge of the shoe contact portion is substantially straight-lined.

40 The cross-sectional formation of the offset rail sections 44 is the same as the widened ends of each transition rail sections, and these offset rail sections are placed between the transition sections; the length of the third rail formed by a series of offset sections depending 45 on the curvature of the railway track, or on switches or cross-overs employed in the track system. In the drawings, parts of the offset sections are designated by numerals corresponding with those applied to corresponding 50 parts of the offset sections.

55 All of the rail sections mentioned are in common use in bottom or under-contact rails, and are well known to those skilled in the art to which this invention relates.

60 Supporting insulators are employed in connection with each supporting bracket 36, and these are in two forms, designated 56 and 57, respectively. The supporting insulators 56 are for straight-line rail sections and each is formed of three sections or parts 58, 59 and 60, while the supporting insulators 57 are for the offset or the transition sections and are formed in two parts 61 and 62.

65 The supporting insulators 56 for the straight-line rail sections may therefore be

said to comprise a head member, referred to as the part 58, and outer and inner side members, referred to as the parts 59 and 60, respectively.

70 The head member 58 comprises a transversely widened solid insulation member whose longitudinal marginal portions 63 overhang the sides of the head 47 of the third rail section with which it is used, and the region of its under surface between said overhanging portions is curved or otherwise formed to conform to the upper surface of said rail. The under surface of said overhanging marginal portions 63 are inclined 75 downwardly from the head of the rail and 80 provided with depending longitudinal flanges 64 spaced from the head of said rail. The upper face of this head portion is provided with a transverse groove 65 which is continued downwardly along the inner or edge 85 face of the head member and said head member is tapered downwardly from said groove toward opposite ends, as at 66. The inner side or edge of said head member bears 90 against the inwardly-facing flat bearing surface 37 of the supporting bracket.

95 The inner sides of the side members 58, 59 have inwardly-projecting portions 67 which enter the depressions in opposite sides of the rail. These inwardly-projecting portions may be termed rail-carrier or supporting portions and they are slightly narrower than the depressions in said rail. Their upper faces or edges are in contact with the under side of the head 47 at opposite sides 100 of the rail. These side members also bear against opposite sides or edges of said head 47 and the shoe contact portion 48 of the rail, and their upper edges are inclined to correspond to the inclined under sides of the 105 overhanging marginal portions of the head member against which they bear. The upper ends of said side members are positioned between the opposite faces of the depending flanges 64 on the head member 58, and they are rabbeted, as at 68, to receive said flanges.

110 The supporting insulators are of a length to extend beyond opposite edges of their supporting brackets, and the outer side member 59 of each insulator applied to a straight-line rail section is provided on its outer face with a longitudinal groove or depression 69, having a downwardly-facing shoulder 70 and into which the ledge or rib 115 39 on the supporting bracket is entered. The downwardly-facing shoulder formed by said depression bears against the upper side of said ledge or rib; thus the outer side member 59 is supported by the supporting bracket 120 37 and is positioned between the latter and the third rail.

125 The inner side member 60 has a groove 71 in its outer face extending from the upper edge of said member downwardly, and this 130

groove terminates in a widened portion 72 having its inner wall inclined outwardly from its upper end and providing downwardly-facing shoulders 73 at said upper end.

The groove 71 is aligned with the groove 65 of the head member 58, and the grooves 65 and 71, including the widened lower end of the latter, are adapted to receive anchoring means in the form of an angular or L-shaped bolt 74 having a screw-threaded cylindrical outer end portion 75 and an angular flat inner end portion 76 provided at its free end with lateral extensions 77. This anchor bolt is fitted into the grooves 65 and 71, and the lateral extensions 77 of said bolt enter the widened lower portion 72 of the groove 71 in the outer side member and have their upper edges in contact with the downwardly-facing shoulders 73 of said outer side member. The screw-threaded cylindrical outer end portion 75 of said bolt is passed through an opening in the supporting bracket 36 and has a nut 78 threaded thereto which, upon being tightened against the bracket, pulls upon the angular bolt 74, drawing the vertical or substantially vertical arm 79 of said angular flat portion 76 upwardly and outwardly, while the substantially horizontal arm 80 of said angular flat portion is drawn outwardly; thus the three sections of the supporting insulator are drawn firmly together; the head member 58 and the outer side member 59 being drawn firmly in contact with each other and against the inwardly facing flat bearing surface 37 of the supporting bracket 36, while the inner side member is drawn against the third rail to assure firm contact between the two and at the same time forcing said inner side member firmly against the inner overhanging marginal portion of the head member. The anchor bolt properly supports said inner side member through the medium of its lateral extensions 77. The main support for the outer side member is therefore established by the lateral extensions or lugs 77 of the anchor bolt, or as it may be termed, the hooked anchor bolt, while the ledge or rib 39 serves as the main support for the outer side member.

In the supporting insulators used in conjunction with the offset or the transition sections of the third rail, one of the parts 61 serves as a combined head member and inner side member, the under side of the head portion 81 having a region conforming to the upper surface of the third rail, and from this region said under side is inclined outwardly toward the inwardly-facing flat bearing surface 37 of the supporting bracket, the inner side portion 82 being integral with the head portion 81 and extending downwardly from said head portion. Said inner side portion 82 has an inwardly-directed projection 83 fitting into the depression at the inner side

of the rail section and against the under side of the head thereof, and it also has at its lower end an inwardly-directed comparatively wide extension 84 which overlies the transversely widened shoe portion 54 and bears against the outer marginal portion thereof.

Like the outer member 59 of the supporting insulator used in conjunction with straight-line rail sections, the outer member 62 is also provided on its outer side with a longitudinal depression 85 forming a downwardly-facing shoulder which bears against the ledge or rib 39 of the supporting bracket, and on its inner side it has an upwardly-projecting portion 85^a which enters the depression in the outer side of the rail section. The upper face or edge of this inwardly-projecting portion is in contact with the under side of the head 47 at the same side of the rail section.

It is to be noted that the outer and inner members 59 and 60 of the supporting insulators extend downwardly along the side of the shoe contact portion 48 of the straight-line rail section, and this is also true of the outer member 62 used in conjunction with a transition or an offset rail section; thus guarding against the elements of the weather coming in contact with the rail. Due to the fact that the wide extension 84 extends over and beyond the inwardly-directed wide part of the shoe contact portion of the transition or the offset rail section, elements of the weather are carried outwardly free of the shoe contact portion of said transition or said offset rail section; especially since the upper surface of said extension is inclined downwardly to its edge, as clearly shown in Fig. 10.

A groove 86 is formed in the head portion 81 of member 61, and this groove is continued downwardly along the outer face of the inner side portion 82, terminating in a wide recess 87 having downwardly-facing shoulders 88 at opposite sides of said recess at the inner wall 89 thereof. Hooked anchor bolts, such as used in conjunction with the supporting insulators of the straight-line rail sections are also employed in the manner described with reference to said straight-line sections and are similarly numbered, and they serve to draw the members 61 and 62 of the supporting insulator against the inwardly-facing flat bearing surface 37 of the supporting bracket and also hold the two members together; thus clamping the offset sections of the third rail in a secure manner between the two members of said supporting insulators.

The rail sections are bonded together as illustrated, for example at 90. Figs. 8 and 12. The supporting insulators 56 and 57 cover practically all except the contact surface of the regions of the third rail to which they are applied, and the insulation covering sections cover the rail between said sup-

porting insulators, excepting only the contact surface thereof.

These insulation covering sections are used in various combinations. For the straight-line rail sections, straight-line covering elements or sections 91 are used, which may be referred to as main sections, due to the fact that these will be used in largest quantities. In conjunction with these straight-line covering elements or sections, comparatively short straight-line bond-covering sections 92 are used; they being placed directly over the ends of straight-line rail sections and abutting correspondingly-shaped ends of transition rail sections bonded together.

In addition to the covering sections 91 and 92, my insulation covering or system includes the use of offset covering sections 93 and offset bond-covering sections 94, both of which are applied to the offset rail sections 44, and wherever offset covering sections are employed in conjunction with the straight-line or main covering sections 91 or a straight-line bonding covering section 92, a transition covering section 95 is used, said transition covering section covering substantially one-half the length of a transition rail section 43, and more particularly, the intermediate portion thereof.

As clearly shown in Fig. 11, each of the main covering sections 91 is of substantially inverted U-formation in cross section providing side walls 96 and a connecting cross or crown wall 97; and projecting inwardly from the side walls 96, a distance from the cross or crown wall equaling the depth of the head 47 of the rail, are retainer elements 98 in the form of lugs molded integral with the side walls and spaced apart, as clearly shown in Fig. 18.

It may here be stated that the insulating supports 56, 57 and all of the covering sections constituting my insulation system are preferably made of rubber and suitable waste material, forming what may be termed a rubber composition, due to the presence of rubber therein. The various rubber composition elements employed are fashioned from thin layers built-up over a form and introduced into a mold, wherein the structure thus created is vulcanized so as to provide the desired finished formation of parts, or walls of each part and accessories thereto. The walls of the covering parts are comparatively thin and are therefore yieldable to pressure, causing the side walls in the main covering sections to separate in applying such sections over a rail section. The inherent resiliency of the covering sections will tend to bring the side walls in firm contact with the sides of the rail at the head 47 thereof and at the shoe contact portion 48, the side walls preferably terminating at their lower ends a short distance above the under or contact surface of the rail. In this manner the side walls over-

lap the sides of the shoe contact portion of the rail and may, if desired, project beneath the contact surface, as this depends considerably on the form or construction of the contact element traveling in contact with the contact surface of the rail. One form of such traveling contact element is shown at 99, Fig. 14, wherein a portion of a locomotive or an attachment to a locomotive is shown carrying said contact element, the portion of the locomotive or the attachment thereto being designated by the numeral 100.

The straight-line bond-covering sections 92 are similar in formation to the main or straight-line covering sections 91, with the exception that the side walls 101 are spaced farther apart and each side wall is provided with vertically-disposed spacing ribs or flanges 102; these being oppositely disposed near each end of the section to form co-acting ribs or flanges near each end of the section. The opposite ribs or flanges are spaced apart the same distance as the side walls of the main or straight-line covering sections 91 so that the side walls of the bonding sections between 90 said spacing ribs or flanges are held spaced from the portions of the rail over which the covering section is applied; this being necessary, due to the fact that the bonding wires 90 extend outwardly beyond the edges or side faces of the head and contact shoe portions of the rail, as clearly shown in Fig. 12. The spacing ribs or flanges 102, only, lie in contact with said edges or side faces, and on each of these spacing ribs or flanges, retainer elements 103 are formed; they being similar to retainer elements 98 on the main covering sections 91.

Due to the fact that the contact shoe portions of the offset rail sections extend laterally at the outer and inner sides of the rail to a greater extent than the contact shoe portion of the straight-line rail sections and that the degree of extension at the inner side is considerably greater than at the outer side, also that the contact surface thereof inclines downwardly from the inner edge of the shoe contact portion to the outer edge thereof, the side walls 105, 106 of each offset section 93 are disposed at obtuse angles to the crown wall 107 of such section, the outer side wall being at a lesser obtuse angle to said crown wall than the inner side wall. These side walls normally assume the same position with relation to the outer edges of the head and shoe contact portions of the offset rail section, as the side walls of the main or straight-line covering sections. The inner side wall 106 inclines under a gradual slope from the head of the rail section to the inner edge of the shoe contact portion; it being consequently necessary to provide the inner side of said inner side wall with a comparatively heavy longitudinally-disposed rib or enlargement 108 of substantial

ly triangular formation in cross-section so as to form a bearing surface which is in firm contact with the adjacent edge or side face of the head of the offset rail. On the under 5 face of said triangular rib or enlargement, substantially triangular lugs 110 are arranged, which are spaced apart along the length of the section and have retainer elements at their inner angles in the form of 10 lips 111, as clearly shown in Fig. 14. The outer side wall also has retainer elements 112 in the form of spaced-apart lugs.

The offset covering sections 93 have their 15 side walls normally approaching each other somewhat closer than shown in Fig. 14, being constructed to operate under the same principle as the main covering sections, in that the side walls must be rigid enough to cause them to be forced outwardly in applying 20 the covering sections to the rail sections; the inherent resiliency of the walls of such offset covering sections causing the retainer elements 111 and 112 to be positively engaged with the under side of the head of the rail section, while the outer marginal portions of 25 the side walls spring against and remain in firm contact with the opposite side edges of the outwardly-inclined shoe contact portion of said rail sections.

The transition covering section 95 comprises a top or crown wall 113 and two side walls 114, 115, one end of each transition covering section conforming in cross section to the cross-sectional formation of the 30 straight-line covering sections, while the other end conforms in cross-section to the cross-sectional formation of the offset sections; thus providing a wide and a narrow end for each transition covering section, 35 with the result that the intermediate portion of each of said sections is gradually narrowed from the wide portion to the narrow portion; this being clearly shown in Figs. 23 to 25. It is to be noted that the side wall 114 40 has substantially parallel end portions which lie against the parallel end portions of the offset rail section shown in Fig. 15, while the intermediate portion of said wall is obliquely disposed to conform to and lie against the 45 intermediate oblique portion of said transition rail section. The side wall 115, which is disposed along the major portion of its length at a greater obtuse angle than the major portion of the side wall 114, gradually 50 approaches a right angular position with respect to the crown wall of said covering section from its greatest obtuse angularity, so that the free longitudinal marginal portion 55 or lower edge portion of this side wall lies against the outer edge of the inwardly-extended part of the shoe contact portion 54.

Like the offset covering section, the inner side wall 115 of each transition covering section has a triangular enlargement 116 on its 60 inner face, gradually reduced in transverse 65

dimension from its wide end to its narrow end, as clearly shown in Fig. 25, and at the apex or inner corner of this triangular enlargement, retainer lugs 117 are provided, which engage the under side of the head of 70 the transition rail section. Directly opposite these retainer lugs 117, similar retainer lugs 118 are formed at the apex or inner corners of a somewhat triangular enlargement 119 formed lengthwise on the inner surface 75 of the outer side wall 114 (Figs. 13 and 25). The triangular enlargements provided on the offset covering sections and the transition covering sections have one of their surfaces serving as a bearing surface, as at 120, 80 and these triangular enlargements may also be referred to as integral fillers, which fill up the space between the normal thickness of the walls on which they are formed, and the edges or side faces of the heads of the several rail sections.

The offset bond covering sections 94 are similar in general cross-sectional outline to the offset covering sections 93, with this exception, however, that the side walls 121, 122 of each of the offset bond covering sections are of uniform thickness throughout their length and width, and that on each side wall adjacent the crown wall 123 of the section, a pair of triangular lugs 124 are formed, 95 each lug having an inwardly-extending retainer lip 125. The retainer lugs of these offset bond covering sections therefore present inclined faces to the corners of the heads of the rails in the same manner as the other 100 covering sections referred to; and as clearly shown in Fig. 2, these triangular lugs, which with the lips 125 extending therefrom, serve as retainer lugs or elements, and they are disposed near opposite ends of the section. 105

As clearly shown, the retainer elements on the opposite side walls of the several covering sections are preferably in transverse alignment, and it is particularly to be noted that before applying the main or straight-line covering sections to the straight-line rail sections, and the straight-line bond-covering sections to the rail sections, the side walls of 110 said covering sections normally incline downwardly and inwardly under the inherent resiliency of the walls of said sections, as clearly shown in Fig. 20. In applying these sections to the third rail, it is necessary to exert force against the side walls from the inner sides thereof to separate them, and by 115 reason of the retainer lugs or elements 98 and 103 being shaped to provide beveled under faces, as at 126, which may be termed "riding surfaces", these bevel faces come in contact with the rounded upper corners of the heads 120 of the rails and by exerting pressure downwardly on the covering sections, cause the side walls to spread apart sufficiently to provide assurance that the lower edges of these 125 side walls will not come in contact with the 130

upper face of the contact shoe portion 48 of the rail and prevent proper seating of the insulation covering on the rail. Moreover, after the covering sections are applied to the rail and the retainer lugs or elements 98 and 103 ride over the sides of the head of the rail, the inherent resiliency of said covering sections cause the side walls to spring inwardly, bringing said retainer lugs or elements firmly against the under side of the head of the rail and the side walls at their lower marginal portions in firm contact with the sides of the shoe contact portion of the rail; thus positively retaining the covering sections on the rail sections in a manner to guard against the elements of the weather coming in contact with the rail and causing short circuits, and at the same time providing an effective and positive insulation guard or protector to prevent accidents to persons whose duties compel them to travel adjacent to or pass over the rails.

It is therefore to be noted that all of the covering sections are adapted to be forced or snapped over the rail under pressure, and that the beveled riding faces of the retainer lugs or elements formed on said sections, all ride in contact with the edges or side faces of the heads of the rail sections, and when exerting pressure against the upper sides of the covering sections, cause the side walls to separate regardless of their normal positions or angularity relatively, with the result that in each instance, as the retainer lugs or elements ride off the edges or side faces of the head of the rail sections, the inherent resiliency of the falls of the covering sections cause the side walls to spring toward the rail sections. No extraneous fastening devices of any kind are therefore required to retain the covering sections on the rail sections.

It is also to be noted that offset rail sections are arranged between straight-line rail sections, and that the transition rail sections are invariably bonded to the offset and straight-line rail sections. The transition rail sections are therefore connectors between the offset rail sections and the straight-line rail sections, and consequently in many cases bond covering sections are disposed at opposite ends of the transition covering sections. The bond covering sections are comparatively short; each straight-line bond covering section overlying the narrow end of a transition rail section and the abutting end of a straight-line rail section, while each offset bond covering section normally overlies the wide end of a transition rail section and the abutting end of an adjacent offset rail section.

It is further to be noted that with the exception of the transition sections I provide each of the covering sections at one or both ends with lap enlargements 127, but such lap enlargements may be employed selectively;

that is to say, one or both ends of the transition covering sections may be provided with lap enlargements and the adjacent ends of adjoining covering sections formed accordingly. These lap enlargements provide internal shoulders 128 in the sections where such enlargements are employed of a width equaling the thickness of the walls of the sections so that the adjacent end of the adjoining section may abut against such shoulders with assurance of contact over a considerable area, thus making a tight joint and preventing ingress of the elements of the weather, especially rain.

While I have illustrated an insulating third rail covering system, showing various forms of covering sections to effectively cover the various forms of rail sections employed on third rails, it may be stated that the transition and off-set rail sections are invariably used at switches or cross-overs, such as shown in Fig. 2, and at such points there are invariably third rail sections employed adjacent the switch portions or cross-overs of the track rails, as shown at 129. These, however, are usually offset rail sections and naturally are provided with offset covering sections; supporting brackets 36 being also employed along these rail sections equipped with supporting insulators 57. The transition and offset rail sections and corresponding covering sections are also employed along curved portions of tracks, as shown in Fig. 5, and as will be understood by those skilled in the art to which this invention relates.

Opposite ends of the supporting insulators 56 and 57 overlie the adjacent ends of the covering sections arranged on the rail adjacent such supporting insulators, as shown at 130, thus the adjacent ends of the adjoining covering sections are overlapped by said supporting insulators in the same manner as one covering section has its end or ends overlapping another.

The rail supporting insulators are also constructed of what may be designated a rubber composition, so termed because of the fact that it contains a quantity of rubber enabling the composition to be molded to desired form and vulcanized. This composition is preferably rubber and waste material, including waste textile material, rubber-coated or plain; it being understood that where rubber-coated waste material, such as waste rubber-aprons and the like, are employed, a smaller quantity of rubber will be required in the composition, but in every case only sufficient rubber is used to assure vulcanization and provide a rigid covering structure having inherent resiliency sufficient to enable the covering sections to be applied to the third rail sections under suitable force, without the use of extraneous fastenings, except in so far as the supporting insulators are concerned.

Having thus described my invention, what I claim is:

1. An insulation covering for third rails of railway systems, formed of insulating material having three walls arranged at angles to each other, said walls having inwardly-projecting retainer elements on their inner sides provided with inclined riding faces adapted to ride in contact with the opposite edges of the head of a third rail under pressure applied to the top of the covering and to engage the under side of said head under the inherent resiliency of said walls.
2. An insulation covering for third rails of railway systems having comparatively rigid walls yieldable relatively and provided with at least one lap end formed by an end enlargement and with an internal shoulder overhung by said end enlargement and against which the end of an adjoining covering section is adapted to bear.
3. An insulation covering for a third rail of railway systems having a laterally projecting head and a shoe contact portion, said covering having comparatively rigid walls yieldable relatively under the inherent resiliency of said walls and provided with internal bearing ribs spaced apart and adapted to bear against the sides of the rail sections to provide a space between the side walls of said covering and the edges of the head and the shoe contact portion of the rail.
4. An insulation covering for third rails of substantially inverted U-formation in cross section to provide a crown wall and two depending side walls, said walls being comparatively rigid and possessing inherent resiliency to permit flexing of said side walls with respect to said crown wall, said side walls being normally inclined inwardly toward each other from said crown wall downwardly and having internal retaining means projecting inwardly and adapted to engage the under side of the head of a rail.
5. An insulation covering for a third rail having a head and a shoe contact portion, comprising a crown wall and side walls arranged at obtuse angles to said crown wall, one of said side walls being at a greater obtuse angle than the other, said walls being comparatively rigid and possessing inherent resiliency to assure inward pressure and permit movement relatively, said side walls being provided on their inner sides with integral longitudinal filler regions adapted to bear against opposite edges of the head of the rail, the lower marginal portions of said side walls being adapted to contact under their inherent resiliency against the edges of the shoe contact portion of the rail, said integral filler regions having retainer lugs adapted to engage the under side of the head of the rail.
6. An insulation covering for a third rail having a head and a shoe contact portion,

comprising a crown wall and side walls arranged at obtuse angles to said crown wall, one of said side walls being at a greater obtuse angle than the other, said walls possessing inherent resiliency assuring inward pressure and permitting relative movement of the lower marginal portions of said side walls to cause contact thereof under inherent pressure of said walls against the edges of the shoe contact portion of the rail, the inner surfaces of said side walls being provided with retainer elements spaced apart and from said crown wall to engage the under side of the head of a rail when the covering is applied thereto.

7. An insulation covering for a third rail having a head and a shoe contact portion, comprising three comparatively rigid walls arranged at angles to each other, one of said walls serving as a crown wall and adapted to lie against the top of the third rail and the remaining walls extending from said crown wall and having free lower marginal portions retained in relative relation under the inherent resiliency of said walls, said remaining walls being adapted to slightly separate when applying the covering to a third rail and being adapted to engage the opposite edges of the shoe contact portion of the rail, said covering having internal retainer means adapted to engage the under side of the head of the rail.

8. An insulation covering for third rails of railway systems, comprising straight-line main covering sections, each of substantially U-formation in cross section, an offset covering section having a crown wall and side walls at obtuse angles to said crown wall, a straight-line bond covering section of substantially inverted U-formation in cross section and of larger transverse dimension than said main sections, an offset bond covering section corresponding in cross section to, but of larger internal transverse dimension than said first-mentioned offset covering section, and a transition covering section gradually reduced in transverse dimension from one end portion thereof to the other and having one end portion thereof conforming in shape to one of said offset bond covering sections and its other end portion to one of said straight-line bond covering sections.

9. An insulating covering for third rails of railway systems, comprising straight-line main covering sections, each of substantially inverted U-formation in cross section, an offset covering section having a crown wall and side walls at obtuse angles to said crown wall, one of said side walls being at a greater obtuse angle than the other, and a transition covering section interposed between said main sections and said offset sections and gradually reduced in transverse dimension from one end portion thereof to the other, said transition covering section having one end portion

thereof conforming to said offset covering sections and its other end to one of said main covering sections.

10. An insulation covering for third rails of railway systems, comprising two series of straight-line main covering sections, each of said sections being of substantially inverted U-formation in cross section, a series of offset covering sections between said two series of main sections, each off-set covering section having a crown wall and side walls at obtuse angles to said crown wall, one of said side walls being at a greater obtuse angle than the other, right and left hand transition covering sections at opposite ends of said series of offset covering sections, each transition covering section being gradually reduced in transverse dimension from one end portion thereof to the other and having one end portion thereof conforming in cross-sectional shape to the adjacent series of main covering sections and its other end to the intermediate series of offset covering sections, the side walls of all of said sections being provided with integral internal retainer elements adapted to engage the under side of the head of a third rail.

11. In combination with an offset third rail having a wide shoe contact at its lower end, said contact being formed by flanges extending outwardly and inwardly, said inwardly-extending flange being wider than said outwardly-extending flange, and said shoe contact having a downwardly and outwardly inclined contact surface, of a supporting insulator encompassing the upper portion of said rail and in contact with the outer edge of said outwardly-extending flange, said supporting insulator having an inwardly-directed comparatively wide extension which overlies the said inwardly-directed flange and bears against the outer marginal portion thereof.

12. An insulation covering for third rails of railway systems, comprising end to end applied sections having comparatively rigid walls yieldable relatively and having said walls of a definite thickness, each section being provided with at least one lap end formed by an end enlargement and with an internal shoulder of a width approximately that of the thickness of the walls overhung by said end enlargement and against which the end of an adjoining covering section is adapted to bear.

13. An insulation covering for third rails of railway systems, comprising straight-line main covering sections, each of substantially U-formation in cross section, and an offset covering section having a crown wall and side walls at obtuse angles to said crown wall.

14. An insulation covering for third rails of railway systems, comprising straight-line main covering sections of substantially U-formation in cross section, and an offset bond

covering section having a crown wall and side walls at obtuse angles to said crown wall.

15. An insulation covering for third rails of railway systems, including an offset covering section having a crown wall and side walls at angles to said crown wall, one of said side walls being at a greater angle than the other.

16. An insulation covering for third rails of railway systems, including a transition covering section comprising a crown wall and side walls and being gradually reduced in transverse dimension from one end portion thereof to the other, the larger end of said section having its side walls at an angle to the crown wall and one of the side walls at a greater angle than the other while the other end of said section has its side walls in such relation to the crown wall so as to form a substantially U-shaped cross section.

In testimony whereof, I affix my signature.
WILLIAM H. FORD.
